CONTAINER LID LIFTING TOOL

Warren Skinner, 1045 Clarendon 39,
Sheridan, Wyo. 82801

Filed Jan. 20, 1975, Ser. No. 542,223

Term of patent 14 years

Int. Cl. D7—06

U.S. Cl. D8—40

Fig. 1.

Fig. 2.

Fig. 3.

Fig. 4.

Fig. 5.

Fig. 6.

FIG. 1 is a perspective view of a container lid lifting tool showing my new design;

FIG. 2 is a top plan view on an enlarged scale of same;

FIG. 3 is a side elevational view of same;

FIG. 4 is a bottom plan view of same;

FIG. 5 is an end elevational view of same taken from the upper end of FIG. 2; and

FIG. 6 is an end elevational view taken from the lower end of FIG. 2.

I claim:

The ornamental design for a container lid lifting tool, as shown.
